UNITED STATES PATENT OFFICE

MACK KINLEY HOPPER, OF MIRANDO CITY, TEXAS

AEROPLANE WING

Application filed June 24, 1929. Serial No. 373,336.

The invention relates to the art of aeronautics and it particularly has for its object to provide a simple and effective wing structure, by means of which the rate of flying speed and the supporting capacity of the machine may be varied without weakening the structure of the wing or adding undue weight to the machine.

Further, it is an object to provide a wing, 10 the lifting surface of which remains rigid while the top surface of which may be raised or lowered to increase or diminish the wind resistance and consequently decrease or increase the speed of the ship.

15 Further, it is an object of the invention to provide a wing of such construction that it may be thickened or thinned at will within certain limits of course, thereby changing its lifting capacity within the range provided.

20 Other objects will in part be obvious and in part be pointed out hereinafter.

To the attainment of the aforesaid objects and ends, my invention consists in the novel features of construction and in combination, 25 connection and arrangement of parts, herein-after more fully described, and then pointed out in the appended claims.

In the drawings:

Figure 1 is a perspective view of a portion 30 of a wing with aileron removed and a portion of the cover broken away.

Figure 2 is a cross section on the line 2—2 of Figure 1.

35 Figure 3 is a cross section on the line 3—3 of Figure 1, the aileron being shown in dotted lines.

Figure 4 is a detail perspective view of the overlapped sheet metal leading edge cover strips.

40 Figure 5 is a detail side elevation of the lower section or body of one of the main ribs.

Figure 6 is a similar view of the upper or adjustable section of one of the main ribs.

45 In the drawings in which like numerals of reference indicate like parts in all of the figures, the wing 1 in my present invention is composed of a set of ribs mounted on longitudinal spars 8. The ribs consist of long ribs used on those portions of the wing not carrying the ailerons, and short ribs used on those

portions of the wing to which the ailerons are attached. Each long rib consists of a lower or main body or section 2 having its rear or trailing edge slotted as at 3 and provided with pin holes 4 for a purpose present- 55 ly explained.

The lower rib body 2 is of skeleton truss form and is provided with fore and aft spar sockets 5 in which the spars 8 are located. The front or leading edges of the rib bodies 2 30 are provided with link pins 6 to which the slotted links 9 are pivoted. Mounted on the lower rib bodies 2, the rear of the front spars, are bearing hangers 7 in which rock shafts 19 are journaled. 55

Each long rib also includes an upper section 10 composed of a bar and suitable braces, the bar being bent to conform to the normal curvature of the upper surface of the wing. Each bar 10 is braced by a vertical 70 brace 12 and fore and aft braces 13 and 14, the braces 12 and the fore and aft braces being connected to brace terminal link connections 11. At the rear ends the upper sections of the main ribs are apertured to receive pins 22 which pass through the apertures 4 in the lower section and serve to hingedly connect the upper and lower rib sections together along their rear edges. 75

At the front the upper rib sections 10 carry 30 link pins 22 that operate in the slotted links 9 hereinbefore referred to and serve to connect the front or leading edges of the upper and lower rib sections together in a manner that they may have limited movement relatively toward and from one another. 35

Where the ailerons are located short rib members are provided. These members consist of lower sections 29 and upper sections 30. The lower sections have spar sockets 31 in 30 which the spars 5—5 lie.

The lower and upper rib sections 29 and 30 are connected together at their leading or front edges by pin and link connections similarly to the long ribs and at the rear the upper rib sections 30 are connected with the lower sections 29 by link pin and slot connections 32 similar to those at the front. In other respects the upper rib sections 30 are similar 35 to those of the long rib sections 10. 300

The upper rib sections are raised and lowered in unison by means of the rock shaft 19 which is provided with a set of adjusting arms 20 connected by links 21 to the several 5 terminal link connections 11.

5 The upper rib sections of the several ribs are connected by fore and aft cross members 15 and 17 respectively, to which the rib members are braced by braces 16 and 18 respectively.

10 The ribs and spars constitute a skeleton which is provided with a cover 24 of the usual kind and at the front or leading edge of the rib there is provided, secured to the upper 15 surface of the wing, a strip 25 of aluminum or other similar material, the lower edge of which projects between the folded strip or plate 26—27 of aluminum or other similar material that is secured to the lower surface 20 of the wing. The purpose of having the edge 25 telescoped into the edges 26 and 27 is to prevent the wind entering the body of the wing.

15 The shaft 19 is turned to adjust the wing, 25 i. e., to raise or lower the upper sections of the ribs and consequently the upper surface of the wing, by a suitable operating mechanism 28 that may be actuated by the operator in the cockpit. This operating mechanism 30 may be of any mechanical type as for instance a crank and gear connection with the shaft 19.

35 From the foregoing description, taken in connection with the accompanying drawings, it will be seen that by turning the shaft 19 in a manner to raise the upper rib sections and consequently the upper surface of the wing, the wing is thickened at the front and greater air resistance is offered, thus reducing the flying speed of the vehicle accordingly.

40 Conversely, lowering the upper surface of the wing thins the cross section of the wing and reduces the air resistance, thereby permitting the vehicle to travel at a greater speed.

45 From the foregoing description, taken in connection with the accompanying drawings, it is thought the construction, operation and advantages of the invention will be clear to those skilled in the art to which it appertains.

50 What I claim is:

1. An aeroplane wing comprising a set of ribs each composed of a lower rigid section and an upper rigid section, means hingedly 55 connecting said sections together at their aft edges, slotted links connecting the fore edges of said upper and lower sections, said lower sections having spar receiving sockets, spars in said sockets for holding several ribs of the set in spaced relation, a covering for the aforesaid structure, and means to raise and lower said upper section.

60 2. An aeroplane wing comprising a set of ribs each composed of a lower rigid section and an upper rigid section, means hingedly

70 connecting said sections together at their aft edges, slotted links connecting the fore edges of said upper and lower sections, said lower sections having spar receiving sockets, spars in said sockets for holding several ribs of the set in spaced relation, a covering for the aforesaid structure, and means to raise and lower said upper section, said covering including overlapped strips at the fore or leading edge of the wing.

75 3. An aeroplane wing comprising a set of ribs each composed of a lower rigid section and an upper rigid section, means hingedly connecting said sections together at their aft edges, slotted links connecting the fore edges of said upper and lower sections, said lower sections having spar receiving sockets, spars in said sockets for holding several ribs of the set in spaced relation, a covering for the aforesaid structure, means to raise and lower said upper section, said covering including overlapped strips at the fore or leading edge of the wing, said strips comprising a single member on the upper part of the wing and a double member on the lower part of the wing, the single member having a sliding fit in the double member.

80 4. An aeroplane wing comprising a set of ribs each composed of a lower rigid section and an upper rigid section, means hingedly connecting said sections together at their aft edges, slotted links connecting the fore edges of said upper and lower sections, said lower sections having spar receiving sockets, spars in said sockets for holding several ribs of the set in spaced relation, a covering for the aforesaid structure, means to raise and lower said upper section, said ribs including 85 long and short ones, the long ones having the spar sockets of the lower sections open at the top.

90 5. An aeroplane wing comprising a set of ribs each composed of a lower rigid section and an upper rigid section, means hingedly connecting said sections together at their aft edges, slotted links connecting the fore edges of said upper and lower sections, said lower sections having spar receiving sockets, spars in said sockets for holding several ribs of the set in spaced relation, a covering for the aforesaid structure, means to raise and lower said upper section, said ribs including 95 long and short ones, the long ones having the spar sockets of the lower sections open at the top, the upper and lower sections of the short ribs having pin and slotted link connections at the rear as well as at the front.

100 6. An aeroplane wing comprising a set of ribs each composed of a lower rigid section and an upper rigid section, means hingedly connecting said sections together at their aft edges, slotted links connecting the fore edges of said upper and lower sections, said lower sections having spar receiving sockets, spars 105

in said sockets for holding several ribs of the set in spaced relation, a covering for the aforesaid structure, means to raise and lower said upper sections, said upper rib sections each including a vertical brace and fore and aft braces connected to a terminal link connection, bearing hangers mounted on the lower rib sections, a rock shaft journaled in said hangers, adjusting arms on said shaft and link-connecting said arms to said terminal link connections.

7. In aeroplane wings, a pair of longitudinal spars, a set of ribs arranged transversely of said spars and spaced apart, a covering over said ribs and spars, each of said ribs comprising a lower rigid body of skeleton structure and an upper body consisting of a long curved rib-bar, a vertical brace, fore and aft braces, and a terminal link connection to which said braces are joined, said upper and lower rib bodies being hinged together at their rear edges, slotted links connecting the fore edges of said upper and lower rib bodies, means mounted on the lower rib bodies and connected to said terminal link connections for raising and lowering said upper rib bodies with respect to said lower rib bodies, longitudinal members connecting the upper rib bodies together fore and aft, and braces connecting said longitudinal members to said upper rib bodies and a covering for the whole.

8. In aeroplane wings, a pair of longitudinal spars, a set of ribs arranged transversely of said spars and spaced apart, a covering over said ribs and spars, each of said ribs comprising a lower rigid body of skeleton structure and an upper body consisting of a long curved rib-bar, a vertical brace, fore and aft braces, and a terminal link connection to which said braces are joined, said upper and lower rib bodies being hinged together at their rear edges, slotted links connecting the fore edges of said upper and lower rib bodies, means mounted on the lower rib bodies and connected to said terminal link connections for raising and lowering said upper rib bodies with respect to said lower rib bodies, longitudinal members connecting the upper rib bodies together fore and aft, and braces connecting said longitudinal members to said upper rib bodies, and a covering for the whole, said covering including telescoping plate strips along the fore or leading edge of the wing, said plate strips being secured respectively to the upper and lower faces of the wing.

MACK KINLEY HOPPER.
